UNITED STATES PATENT OFFICE.

FRANK N. POULALION, OF DES MOINES, IOWA.

ILLUMINATED SIGN.

1,139,222.

Specification of Letters Patent. Patented May 11, 1915.

Application filed March 27, 1914. Serial No. 827,635.

To all whom it may concern:

Be it known that I, FRANK N. POULALION, a citizen of the United States, residing in Des Moines, in the county of Polk and State 5 of Iowa, have invented certain new and useful Improvements in Illuminated Signs, of which the following is a specification.

This invention relates to signs of the class adapted for use both by day and at 10 night and particularly to signs of this class in which part of the sign is permanently illuminated at night while another part is alternately lighted and extinguished for the purpose of more certainly attracting the 15 attention of the passers-by.

In carrying out my invention, I provide a casing equipped with means for suspending it from a suitable support, and on opposite sides of this casing I arrange signs, 20 parts of which are transparent or translucent to permit the passage of light from electric lamps or other illuminating means within the casing. In the upper part of the casing I arrange signs which are permanently 25 visible either by day or by night and below the permanent signs I mount other signs which likewise have transparent or translucent parts but which are at times closed to the passage of light through them by covers arranged within the casing. 30 These covers are provided with reflecting surfaces so arranged that when they are withdrawn from the signs which they at times cover light may be reflected through the signs. The covers are preferably alternately opened and closed at short intervals by motor devices located between them.

In the accompanying drawings: Figure 40 1 shows a front elevation of a sign embodying my improvements. Fig. 2 shows a vertical section thereof with the covers of the lower signs closed. Fig. 3 shows a vertical section with the covers open. Fig. 4 is a 45 detail view of part of the upper sign. Fig. 5 shows a section on the line 5--5 of Fig. 4.

The sign shown has a casing or frame A constructed of any suitable material and is preferably given a rectangular form or 50 shape, as illustrated. It may be supported or suspended in any suitable way as by means of hangers B, depending from a horizontally arranged rod C. The upper portion of the sign has on opposite sides sign 55 plates D having transparent or translucent designs, letters or characters d, and between

such sign plates are located a suitable number of electric lamps or other illuminating devices E. The designs, letters or characters d may be formed in various ways but 50 preferably in the manner indicated in Figs. 4 and 5 where glass lenses d' are shown set in suitable frames. The upper signs just described are visible and perfectly plain during the day without the use of lights between them and at night are permanently 55 illuminated. Below the upper permanent signs are arranged the intermittently visible signs F which are disposed on opposite sides of the casing and are provided with 70 transparent characters, designs or letters f which when exposed to the rays of light from the lamps E are plainly visible.

H, H' indicate covers for the signs F. These are made of any suitable material but 75 are provided with reflecting surfaces on their outer sides. The covers are hinged at their lower ends h, h' and when erect, as shown in Fig. 2, shut off the passage of rays of light from the lamps through the signs, 80 but when the covers are swung on their hinges and moved to the position shown in Fig. 3 light is transmitted through the signs, being reflected from the outer surfaces of the covers and thus made most 85 brilliant. The attention of passers-by is apt to be more certainly attracted if the signs or parts thereof are intermittently displayed and withdrawn and in order to do this I provide means for opening and 90 closing the covers at short intervals. The covers may be so held as to normally or when unsupported occupy the open position shown in Fig. 3 but I preferably employ a spring S to hold the covers in the open 95 position shown in Fig. 3. In order to move them to their closed position I employ a cam I attached to a rod or shaft i carrying a pulley z, connected by a belt J to a motor such as an electric motor K. If a slow 100 movement be given to the motor the cam I will be slowly revolved and the covers will be moved alternately to open and closed position, and this causes the signs F to be alternately displayed and withdrawn from 105 view.

A sign made in accordance with my invention may be constructed at small cost; it does not involve the use of switch mechanism incident to signs of this class, and yet 110 it performs the functions for which it is intended with accuracy and economy. The

signs may all be plainly seen both by day and at night from either side and the attention of passers-by is always attracted by means of that part of the sign which is alternately displayed and withdrawn from view.

I claim as my invention:

A sign, comprising a casing, sign plates on opposite sides thereof, spaced apart and 10 having light pervious characters thereon, covers for said sign plates having a space between them, an elongated cam mounted to

rotate in said space between the covers directly engaging the covers and at times holding them in closed position, means for 15 rotating said cam and a spring for moving the covers to open position when released by the cam.

In testimony whereof, I have hereunto subscribed my name.

FRANK N. POULALION.
